GAUGE REEL BRAKE AND WIPER

Jason E. Higgins, Kermit, Tex.

Application January 12, 1951, Serial No. 205,667

1 Claim. (Cl. 242—84.8)

1

This invention relates to a measuring tape or gage reel.

An object of this invention is to provide in a measuring tape a brake means whereby the rotation of the reel may be braked as the tape is being unwound therefrom.

Another object of this invention is to provide in a measuring tape, means for wiping liquids, such as oil, from the tape as the latter is being rewound on the reel.

A further object of this invention is to provide a tape wiping attachment which can be easily mounted on the present structure of a tape reel without altering the parts of the reel.

A further object of this invention is to provide a tape braking attachment for a tape reel whereby the unwinding of the tape may be braked.

With the above and other objects in view, my invention consists in the arrangement, combination and details of construction disclosed in the drawings and specification, and then more particularly pointed out in the appended claim.

In the drawings:

Figure 1 is a longitudinal section taken substantially on the line 1—1 of Figure 2 of a measuring tape reel structure constructed according to an embodiment of this invention.

Figure 2 is a fragmentary sectional view taken on the line 2—2 of Figure 1.

Figure 3 is a fragmentary sectional view taken on the line 3—3 of Figure 1.

Referring to the drawing, the numeral 10 designates generally a frame structure which is formed of a pair of opposite side members 11 and 12 and opposite end members 13 and 14. A tape carrying drum 15 is fixedly mounted on a shaft 16 which extends between the side members 11 and 12, and a crank or handle 17 is secured to one end of the shaft 16.

An elongated length of flat tape 18 is wound about the drum 15 and is adapted to be extended downwardly between the side members 11 and 12 at the rear or handle end of the frame as shown in Figure 1. A handle 19 which includes a threaded stud 20 is removably threaded into the rear end wall 14 and extends lengthwise of the side members 11 and 12.

In order to provide a means whereby the unwinding of the tape 18 may be retarded particularly after a substantial amount of tape has been unwound from the drum 15, I have provided a brake structure which includes a longitudinally bowed resilient carrier 21 which is formed of a flat strip of resilient metal.

2

The carrier 21 is secured at one end as indicated at 22 to the end wall 13 and extends upwardly with the concave side thereof innermost partially about and above the tape 18 which is wound on the drum 15. The rear portion of the carrier 21 is reversely bowed as indicated at 23 and extends in the direction of the handle 18 so that the rear extension 23 which also forms a brake operating handle will be disposed in a convenient position for engagement by a finger or thumb of a hand which may be grasping the handle 19. A longitudinally curved brake element 24 in the form of a body of rubber or the like is disposed on the inner side of the carrier 21 being secured thereto by a fastening member 25. The carrier 21 is formed with a pair of downwardly extending ears or retaining members 26 engaging on opposite sides of the brake element 24 so as to hold the latter against turning movement with respect to the securing member 25 and the carrier 21.

The retaining members 26 as shown in Figure 3 project downwardly or inwardly below the brake element 24 so as to partially straddle the adjacent windings of the tape 18 and thereby assure full contact of the brake element 24 with the tape 18.

The frame structure 10 also has secured thereto a tape wiper attachment constructed in the form of a U-shaped member generally designated as 27. U-shaped member 27 is formed of a pair of parallel plates 28 which are connected together by a connecting member 29. The connecting member 29 engages against the rear side of the rear wall 14 and is formed with an opening 30 through which the threaded stud is adapted to engage so that when the handle 19 is secured by means of the stud 20 to the frame 10, the connecting member 29 will also be firmly secured to the frame 10. The carrier or U-shaped member 27 includes a downwardly extending arm 31 integral with each plate 28 and a flexible roller 32 is rotatably mounted on a shaft 33 extending between the ears or arms 31. The roller or wiper member 32 is disposed in a position to engage the inner side of the tape 18 as the latter is extended from the drum 15.

A second wiping roller 34 is rotatably mounted on the shaft 35 extending between the pair of ears 36 which are carried by a downwardly projecting lever 37. The lever 37 extends loosely between the frame members 11 and 12 and projects upwardly to a point above the upper edges of the frame members 11 and 12. The two plates 55 18 are provided with a pair of upwardly project-

ing ears 38 between which a shaft 39 engages and the lever 37 is provided with a pair of forwardly projecting ears or lugs 40 which rotatably engage the shaft 29. A spring 41 engaging about the shaft 39 constantly urges the lever 37 rearwardly at its lower end so as to thereby normally hold the movable or swingable wiping roller 34 out of contact with the outer side of the tape 18.

The upper end of the lever 37 terminates in a rearwardly and angularly projecting handle or bellcrank member 42 which extends between the handle 23 and the handle 19 so that the handle or operator 42 may be engaged by a finger or thumb of a hand grasping the handle 18 so as to rock the handle 42 downwardly at its rear end and thereby swing the lower end of lever 43 forwardly until roller 34 engages with the outer side of the tape 18 where the tape is passing over the inner roller 32.

In the use and operation of this device the 20 brake attachment is secured to the frame 10 by the securing member 22 so that the brake element 24 will be disposed over the tape which is wound on the reel or drum 15. The brake element 24 is normally disposed out of engagement 25 with the tape by reason of the resiliency of the carrier 21.

As the tape 18 is unwound and is extended downwardly over the roller 32 which initially constitutes a guide roller, the weight of the extended portion of the tape will tend to cause continued unwinding of the tape until substantially all of the tape has been unwound. In order, therefore, to provide for stopping or retarding the rotation of the reel, the carrier 21 is pressed 30 inwardly by a finger engaging the operator 23 so that the brake element 24 will come into braking engagement with the outer side of the tape remaining on the drum 15.

A tape measure of this kind is frequently used 40 in oil wells or other liquid receptacles or containers for measuring the liquids, and these liquids may be wiped from the tape as the latter is being wound on the reel or drum 15 by pressing the lever or arm 42 downwardly and causing wiping roller 34 to swing forwardly into wiping engagement with the outer side of the tape.

The roller 34 will press the tape against the inner roller 32 so that any liquids adhering to the tape will be wiped from the tape as the reel is being wound up through the medium of the crank 17.

What is claimed is:

In combination, a measuring tape structure comprising a frame formed of parallel opposite sides, and opposite ends, a supporting handle for said frame, a threaded stud carried by said handle engaging one of said ends, a tape drum rotatably disposed between said sides, a tape wound on said drum, a crank fixed relative to said drum, a U-shaped member straddling said one end, said stud extending through the bight of said member, a wiping roller rotatably carried by said member and engageable with one side of the tape, a spring-pressed lever rockably disposed between the sides of said member and depending between the sides of said frame, a finger engageable handle on said lever extending out of said frame, a second wiping roller carried by the lower end of said lever confronting the other side of the tape, a brake member carried by said frame and a second finger engaging handle on said brake member adjacent said first finger engaging handle in parallel relation thereto, whereby compression of said handles between the thumb and the forefinger may be effected while holding said supporting handle in the hand, simultaneously effecting engagement of said wiping rollers and said brake member with said tape, and release of said handles disengaging both said rollers and said brake to facilitate movement of said tape.

JASON E. HIGGINS.
